UNITED STATES PATENT OFFICE.

ALEXANDRE DAUVILLIER, OF PARIS, FRANCE.

TELEVISION PROCESS AND MEANS OF REALIZATION.

Application filed August 22, 1924, Serial No. 733,651, and in France November 29, 1923.

The present invention describes a new television process, which is characterized by the fact that the image to be transmitted is analyzed by means of a rotating or oscillating light-distributor selecting at every instant in itself, a spot of invariable size, the coordinates of which varying in its plane according to an arbitrary law, relatively to a system of reference connected with the image; this distributor simultaneously producing currents of variable positions according to the variations of position of the spot relatively to the surface of the image, whose amplitudes are proportional to the said coordinates; the photoelectric current of "elementary brightness" controlling at the receiving station, by known means, the brightness of a luminous spot projected on a screen and put in the correct position by the varying currents. It is this direct production of the varying currents without any auxiliary device, which is the object of the invention.

In the form of construction illustrated the light-distributor of the transmitting apparatus is the revolving opaque disc described in the French Patent Dauvillier No. 521,746 dated 20th August 1915, for the purpose of analyzing a Röntgen image in space and time. This disc 21 has the same number of small holes 41—of the spot size—as there are concentric bands cut out in the image, the holes being angularly equally distant on a single spiral line 43, such that the entire image is explored in one revolution. This disc is placed in the image plane of the objective lens 1. Any optical system can be placed between the disc and the photo-electric cell 2.

The coordinates E. M. F.'s are related to a Cartesian system of coordinates having as reference axes two rectangular sides $0x$ and $0y$ of the image. They are produced by the angular displacements of the disc driven by any sort of motor inside a double fixed collector 44 and 45, a brush 46 carried by the disc introducing into two "coordinate circuits," either: 1, identical elements of E. M. F. 47 connected in series in the "ordinate circuit" 38 (ring segments 48 without resistance) and identical elements of potential difference with a linear variation (revolving potentiometer) in the "abscissæ circuit" 39 (ring segments 49 of high resistance), or: 2, constant elements of resistance for ordinates

and variable elements for abscissæ, storage cells being inserted in the "coordinate circuits"; the result being that in a complete revolution of the disc, the ordinate E. M. F.'s having taken the same number of constant values differing by the same quantity (step variation) as there are holes in the disc, and the "abscissæ" E. M. F.'s having varied linearly the same number of times between zero and the same maximum value (or inversely). These E. M. F.'s present thus variations following the same law as that of the exploration of the image and with amplitudes proportional to the coordinates of the spot. The photoelectric E. M. F. produced by the spots of light from the objective 1 by the disc 21 on the cell 2 may be amplified by any known process such as the triode resistance amplifier of several steps shown at 3. This photoelectric E. M. F. controls at the receiving station, thru the wires 60 and 61, the instantaneous brightness of the cathodic stream of a Braun tube 16. This control is effected by applying the E. M. F.'s between the hot wire cathode 17 and the grid diaphragm 19 with resistance shunt 20 to prevent the accumulation of electrostatic charges.

The coordinate E. M. F.'s or varying currents produced by the brush 46 revolving with the disc 21 position the cathodic stream in the Braun tube thru the wires 38, 39 and 40 connected to the condenser plates 51, the diaphragm tube 47 and the condenser plates 50. The plates of condensers 51 and 50 are arranged at right angles to each other as well known.

From the above it will be seen that the image is reproduced by the cathodic stream of the Braun tube which is varied in intensity by the currents from the photoelectric cell and positioned by the coordinate E. M. F.'s.

The moving brush of the apparatus can be a very fine mercury jet in an hydrocarbide atmosphere (Blondel) or a cathodic stream revolving or at rest.

In both these forms of realization, the cathode ray oscillograph can also be replaced by two ordinary oscillographs placed at right angles and carrying mirrors or slits, or by tuning forks of the same frequencies as those of the distributor and maintained in series by the same plate current. The photo-electric current thus controls the intensity of a beam of light by

means of an electro-optical phenomenon free from inertia as that of Kerr.

Finally the disc described above can form the rotor of a "fork operated chronometric motor" (Guillet) in series with identical and synchronous receiving discs, all being maintained by the same plate current of a triode or by an auxiliary synchronizing fork. The sinusoidal plate current is then 10 the "coordinate current," if time has for all discs the same origin. But this arrangement demands a spontaneous and simultaneous starting for all motors or a device permitting the finding and catching up of 15 the spot.

Polychrome television is obtained by putting in the plane of a first, real auxiliary image a three colour screen whose elementary monochrome grains are proportional to 20 the size of the spot. A similar screen is put in front of the receiving screen (the fluorescent material will then give white light) and can be displaced in two rectangular directions by an amount equal to once 25 or twice the size of the spot.

Wireless television is obtained by the modulation of trains of undamped waves of different frequencies by the "brightness" and "coordinates" currents, these wave 30 trains being filtered at the receiving station by known methods.

What I claim as my invention and desire to secure by Letters Patent is:

1. In a television system, a disc rotating 35 in front of the real image to be transmitted, holes distributed both on a spiral and on concentric and equidistant circumferences drawn on the rotary disc so as to select, at every instant, a beam, of invariable size, completely exploring the plane of the 40 image for a single revolution of the disc, and means allowing the rotary disc to simultaneously produce currents the intensities of which are proportional to the variations of coordinates of the beam relative to 45 the image to be transmitted.

2. In a television system, a disc rotating in front of the real image to be transmitted, holes distributed both on a spiral and on 50 concentric and equidistant circumferences drawn on the rotary disc so as to select, at every instant, a beam, of invariable size, completely exploring the plane of the image for a single revolution of the disc, a photo- 55 electric cell receiving the light stream which passes through the holes of the rotary disc, means for amplifying the current thus produced, a cathodic oscillograph, at the receiving station, receiving the current thus amplified which produces variations of intensity of the cathodic stream produced, and means allowing the rotary disk to simultaneously produce currents which act on the 60 said cathodic stream and the intensities of 65 which are proportional to the variations of

the coordinates of the beam movable in the plane of the image to be transmitted.

3. In a television system, a disc rotating in front of the real image to be transmitted, holes distributed both on a spiral and on 70 concentric and equidistant circumferences drawn on the rotary disc, so as to select, at every instant, a beam, of invariable size, completely exploring the plane of the image for a single revolution of the disc, a photo- 75 electric cell receiving the light stream which passes through the holes of the rotary disc, means for amplifying the current thus produced, a cathodic oscillograph, at the receiving station, receiving the current thus amplified which produces variations of intensity of the cathodic stream produced, means allowing the rotary disc to simultaneously produce a current which varies in arithmetic 80 progression according to the variations of ordinates of the beam movable in the plane of the image to be transmitted and a current which varies in steps according to the variations of abscissæ of the said beam. 85

4. In a television system, a disc rotating in front of the real image to be transmitted, holes distributed both on a spiral and on concentric and equidistant circumferences drawn on the rotary disc so as to select, at every instant, a beam, of invariable size 90 completely exploring the plane of the image for a single revolution of the disc, a photo-electric cell receiving the light stream which passes through the holes of the rotary disc, means for amplifying the current thus produced, a cathodic oscillograph, at the receiving station, receiving the current thus amplified which produces variations of intensity of the cathodic stream produced, a double brush moving at the same time as the 95 rotary disc, a fixed commutator having contacts corresponding to the holes of the rotary disc, elements of constant electromotive force connecting the consecutive contacts in order to produce currents of ordinates 100 varying in arithmetic progression, and means for simultaneously producing a current which varies in steps according to the variations of abscissæ of the beam moving 105 on the image to be transmitted. 110

5. In a television system, a disc rotating in front of the real image to be transmitted, holes distributed both on a spiral and on concentric and equidistant circumferences drawn on the rotary disc so as to select, at 115 every instant, a beam, of invariable size, completely exploring the plane of the image for a single revolution of the disc, a photo-electric cell receiving the light stream which passes through the holes of the rotary disc, 120 means for amplifying the current thus produced, a cathodic oscillograph, at the receiving station, receiving the current thus amplified which produces variations of intensity of the cathodic stream produced, a 125

means for amplifying the current thus produced, a cathodic oscillograph, at the receiving station, receiving the current thus amplified which produces variations of intensity of the cathodic stream produced, a 130

double brush moving at the same time as the rotary disc, a fixed commutator having contacts corresponding to the holes of the rotary disc, elements of constant electro-motive force connecting the consecutive contacts in order to produce currents of ordinates varying in arithmetic progression, a second commutator parallel to the first commutator, insulated contacts corresponding to the holes of the disc and connected in shunt to the terminals of a source of current so as to produce a current which varies in steps according to the variations of abscisse of the beam moving on the image to be transmitted.

In testimony whereof I have signed my name to this specification.

ALEXANDRE DAUVILLIER.
